US00D546774S

(12) **United States Design Patent** (10) **Patent No.:** **US D546,774 S**
(45) **Date of Patent:** **** Jul. 17, 2007**

(54) **POWER PRODUCTION DISPLAY FOR A GENERATOR**

(75) Inventor: **Jere B. Albright, Jr.**, Kearney, NE (US)

(73) Assignee: **Powermate Corporation**, Aurora, IL (US)

(**) Term: **14 Years**

(21) Appl. No.: **29/245,524**

(22) Filed: **Dec. 22, 2005**

(51) **LOC (8) Cl.** **13-03**

(52) **U.S. Cl.** **D13/162**

(58) **Field of Classification Search** **D13/152, D13/158-168, 177, 184; D14/137-139, D14/151, 167, 168, 172, 174, 191-193, 214, D14/217, 218, 240; 361/600, 622, 678, 681; 345/173; 338/153; 174/66; 200/5 A; D10/49, D10/50**

See application file for complete search history.

(57) **CLAIM**

The ornamental design for a power production display for a generator, as shown and described.

DESCRIPTION

The FIGURE is a front view of a power production display for a generator, showing my new design.

The broken line showing of a perimeter surrounding the claimed design is included for the purpose of illustrating environmental detail and forms no part of the claimed design.
